United States Patent Office

Des. 181,535
Patented Nov. 26, 1957

181,535

DEODORANT HOLDER OR SIMILAR ARTICLE

Morris B. Klasky, Downey, Calif., assignor to Klasco Products Co., Inc., Downey, Calif., a corporation of California

Application November 19, 1956, Serial No. 43,829

Term of patent 14 years

(Cl. D16—2)

FIG. 1.

FIG. 2.

FIG. 3.

FIG. 4.

FIG. 5.

FIG. 6.

Fig. 1 is a perspective view of a deodorant holder, or similar article, embodying my new design;

Fig. 2 is a top plan view thereof;

Fig. 3 is a side elevational view thereof taken from the left of Fig. 1;

Fig. 4 is an elevational view of the other side;

Fig. 5 is a rear elevation view; and

Fig. 6 is a bottom plan view thereof.

I claim:

The ornamental design for a deodorant holder or similar article, substantially as shown.
